H. FROOD.

LAMINATED SPRING.

APPLICATION FILED AUG. 8, 1917.

1,254,493.

Patented Jan. 22, 1918.

Inventor:

Herbert Frood
By his Attorneys
Rosenbaum, Stockmire & Shore

UNITED STATES PATENT OFFICE.

HERBERT FROOD, OF CHAPEL-EN-LE-FRITH, ENGLAND.

LAMINATED SPRING.

1,254,493.

Specification of Letters Patent. Patented Jan. 22, 1918.

Application filed August 8, 1917. Serial No. 185,177.

To all whom it may concern:

Be it known that I, HERBERT FROOD, a subject of the King of Great Britain and Ireland, and a resident of Chapel-en-le-Frith, 5 in the county of Derby, England, have invented certain new and useful Improvements in or Connected with Laminated Springs, of which the following is a specification.

10 This invention relates to laminated springs and has special reference to interleaving (particularly woven or fibrous interleaving) which is inserted between the leaves of such springs to prevent contact between the 15 leaves and consequent noise and wear and to insure smooth working. The object of the invention is to provide improved and simple means for retaining the interleaving in position between the leaves of the spring 20 and preventing it from working out laterally.

According to this invention, I provide the interleaving with beaded or other enlarged edges which lie immediately outside of the 25 edges of the leaves of the spring.

In the accompanying drawing, Figure 1 is an elevation of a laminated spring to which is applied a woven interleaving in accordance with the invention, Fig. 2 a cross- 30 section thereof, and Fig. 3 a part perspective view of the interleaving. Figs. 4 to 10 inclusive are part perspective views of modified forms of beaded-edged interleaving according to the invention.

35 Referring to the drawing, *a*, Figs. 1 and 2, is the interleaving arranged between the leaves *b* of the spring and provided with beaded or enlarged edges *c* which lie immediately outside the sides of the leaves.

40 The beaded or enlarged edges *c* may be formed in any suitable way. For example, I may inclose wire, string, thin cord or other suitable material *d* along the edges of the interleaving *a* either during the weaving of 45 the latter, as in Fig. 3, or by turning the edges *a*¹ of the interleaving over the wires, cords or the like *d* and securing them by sewing, as in Fig. 4. Or I may make the interleaving sufficiently wide and fold or 50 turn over the edges *a*¹ thereof one or more times and secure the folded or turned over edges by sewing, as in Fig. 5, or otherwise suitably. Or, as shown in Fig. 6, the inter-

leaving *a* may be woven with pockets *e* along its edges for the subsequent reception 55 of wires, strings or other thickening means. Or I may sew along the edges *a*¹ of the interleaving folded or doubled separate pieces of similar or other suitable fabric, or flat or round cord, braid or the like *a*², as in 60 Fig. 7.

The beaded or enlarged edges may be applied to interleaving composed of thin plates or strips of metal or other suitable material. In such cases, the beaded or enlarged edges 65 *c* may be integral with the interleaving *a*, as shown in Fig. 8, or be formed by narrow strips *a*³ of metal or other suitable material attached to the interleaving by rivets *f*, as in 70 Fig. 9, or in other suitable fashion.

The beaded or enlarged edges *c* are preferably continuous though, if desired, they may be interrupted at intervals, as illustrated in Fig. 10.

It will be seen that when the interleaving 75 *a* is arranged between the leaves *b* of the spring, the beaded or enlarged edges *c* lying immediately outside the edges of the leaves, prevent lateral displacement of the interleaving and retain it in position. Further, 80 the beaded or enlarged edges give a neat appearance to the spring.

What I claim as my invention, and desire to secure by Letters Patent is:—

1. An interleaving for laminated springs 85 provided at its edges with enlargements.

2. In a laminated spring, strips of interleaving arranged between the leaves of the spring and provided with enlargements at their edges, which enlargements lie outside 90 of the leaves and prevent lateral displacement of the strips of interleaving.

3. An interleaving for laminated springs composed of textile material and provided at its edges with enlargements. 95

4. In a laminated spring, strips of interleaving composed of textile material arranged between the leaves of the spring and provided with enlargements at their edges, which enlargements lie outside of the leaves 100 and prevent lateral displacement of the strips of interleaving.

In witness whereof I have hereunto set my hand.

HERBERT FROOD.
